(57) **CLAIM**

The ornamental design for a mobile phone, as shown and described.

DESCRIPTION

1. Mobile phone

1.1 : Front view shown in a folded state with the integral camera retracted

1.2 : Back view thereof

1.3 : Left view thereof

1.4 : Right view thereof

1.5 : Top view thereof

1.6 : Bottom view thereof

1.7 : Front perspective view thereof

1.8 : Back perspective view thereof

1.9 : Front view shown in a folded state with the integral camera extended

1.10 : Back view thereof

1.11 : Left view thereof

1.12 : Right view thereof

1.13 : Top view thereof

1.14 : Bottom view thereof

1.15 : Front perspective view shown in an unfolded state with the integral camera retracted

1.16 : Back perspective view shown in an unfolded state with the integral camera retracted

1.17 : Front view shown in an unfolded condition with the integral camera extended

1.18 : Back view thereof

1.19 : Left view thereof

1.20 : Right view thereof

1.21 : Top view thereof

1.22 : Bottom view thereof
